SKEIN DYEING APPARATUS

Angelo Soriano, Brooklyn, N. Y.

Application February 18, 1937, Serial No. 126,364

4 Claims. (Cl. 68—211)

This invention relates to an apparatus for "spot dyeing" skeins of textile material; that is, dyeing longitudinally spaced portions of said skeins either the same or a variety of different colors or shades.

The invention broadly comprehends an apparatus of the character and for the purpose set forth which includes means for sealing off and isolating one or more longitudinally spaced portions of one or more skeins of textile material within dye receiving compartments, means for completely filling said compartments with dye solution of the same or different colors or shades so that said sealed off isolated skein portions are immersed in the dye solutions, and means for removing the dye solutions from the compartments to permit of the unsealing and removal of the skeins from the apparatus or the shifting of the same with respect thereto to dispose other longitudinally spaced portions in a position for sealed off isolation and dyeing.

More particularly the invention resides in an apparatus of this nature which includes a pair of separable blocks having a plurality of dye receiving recesses in the confronting faces thereof between which faces the skeins are arranged with portions thereof traversing the recesses, yieldable gaskets being provided on the confronting faces of the dye blocks, framing the recesses together with means for forceably compressing the gasket confronting faces into intimate sealing contact to seal off and isolate the longitudinally spaced portions of the skeins, with valved means for gravitationally supplying dye to and filling the recesses, valved means for venting the recesses and for indicating when the same are filled and valved means for draining the excess dye from the recesses after the skein portions have been impregnated.

The invention furthermore embodies means for introducing air pressure to the dye receiving recesses when filled with the dye and sealed so as to more rapidly effect the impregnation of the skein portions and for subsequently effecting the removal of the excess dye and causing a more rapid oxidation or setting of the dye impregnated portions of the skeins whereby they may be removed.

Other features of the invention reside in an improved apparatus of this character by virtue of which the operations of positioning the skeins for dyeing, subjecting them to and thoroughly impregnating them with the dye, effecting the removal of the excess dye therefrom and causing the oxidizing or drying of the dye impreg-

nated portion or portions of the skeins to permit of their removal, may be expeditiously accomplished without material loss of the dyeing solutions, while confining the dye more precisely to predetermined portions of the skeins.

Other objects of the invention are to provide an apparatus of this nature which is not unduly complicated either in its construction or mode of use, which is capable of economical production and assembly and which is highly efficient for its intended purpose.

With these and other objects in view, reference is now made to the following specification and the accompanying drawings in which there is disclosed one embodiment of the invention, while the claims cover variations and modifications falling within the scope of the invention.

In the drawings:

Fig. 1 is a front view of a "spot dyeing" apparatus constructed in accordance with the invention and illustrating the skeins in position for dyeing.

Fig. 2 is a top plan view thereof.

Fig. 3 is a horizontal sectional view taken approximately on the line 3—3 of Fig. 1 and illustrating the lower block swung to a position for facilitating the emplacement or removal of the skeins.

Fig. 4 is a vertical transverse sectional view taken approximately on the line 4—4 of Fig. 2.

Fig. 5 is a vertical sectional view taken approximately on a plane indicated by the line 5—5 in Fig. 2.

While obviously the apparatus may be employed for dyeing one portion of the length of one skein at one time, from a practical standpoint it is herein illustrated and intended to be utilized for simultaneously dyeing a plurality of longitudinally spaced portions of each of a number of skeins, a variety of different colors or shades.

Referring to the drawings by characters of reference, 10 designates the base of the apparatus which is provided with laterally spaced upright supports 11 and 12 having horizontal upper supporting surfaces 13 and 14. A pair of arms 15 and 16 are secured to the supports 11 and 12 respectively and protrude upwardly therefrom, the upper ends being provided with reduced threaded upper extremities 17 which receive thereover the apertured terminals of a cross head 18 having a central hub 19 provided with a vertical internally threaded bore 20. A threaded shaft 21 engages with the bore 20, is provided with a manipulating wheel 22 at its upper end and is connected at its lower end by 65

a swiveled connection 23 with a pressure plate 24 which is mounted for guided vertical movement on the arms 15 and 16 which extend through guide openings 25 and 26 in the pressure plate.

The apparatus further includes a pair of dye blocks 30 and 31, the former being hereinafter termed the lower dye block and the latter the upper dye block. The lower dye block 30 is provided with a vertical opening 32 through which the arm 15 extends and normally rests upon the upper supporting surfaces 13 and 14 of the supports 11 and 12, but is capable of being swung to a position to disengage the upper surface 14 of the support 12 so as to permit of the positioning of the skeins thereover in surrounding relation thereto. The upper dye block 31 is mounted for vertical guided sliding movement on the arms 15 and 16 which extend through vertical guide openings 33 and 34 and said upper dye block is detachably connected with the pressure plate 24 by suitable means, such as the swinging hooks 35 fulcrumed on the pressure plate 24 and engaging with eyes 36 on said upper dye block.

As illustrated, the confronting faces of the upper and lower dye blocks 30 and 31 are provided with a plurality of confronting mating recesses 40 and 41, 42 and 43, and 44 and 45, it being obvious that one or more pairs of mating recesses may be provided in said dye blocks within the scope of the invention. It will also be apparent that the recesses may be varied in size as well as the number employed and that the dye blocks may be of any practical length depending upon the number of skeins which are to be simultaneously dyed by the apparatus.

The confronting faces of the blocks are each provided with yieldable sealing gaskets 46 and 47 which are provided with mating slots 48 conforming to the contour of the recesses so that the same are framed by the gasket material which is preferably a good grade of Pará rubber and which is secured in place in any suitable manner, such as by screws or other equivalent fastening means 49 which are threaded into wooden plugs 50 counter-sunk in depressions in the confronting faces of the dye blocks.

The skeins of textile material, which are designated by the reference character S, are preferably arranged in surrounding relation to the lower dye block 30 as particularly illustrated in Fig. 5 of the drawings, so that the upper leads thereof traverse the upper face of the lower dye block with longitudinally spaced portions P thereof traversing each of the recesses 40, 42 and 44. The emplacement of the skeins S is effected by swinging the lower dye block to a position out of contact with the support 12, as shown in Fig. 3 of the drawings. After the skeins have thus been emplaced, the dye block is swung to its normal position resting upon and supported by the upper surfaces 13 and 14 of the supports 11 and 12. The upper dye block which has been elevated to permit of the emplacement of the skeins, is then lowered by means of the threaded shaft 21 and the gasketed lower surface of the upper dye block is forceably compressed against the gasketed upper face of the lower dye block to seal off and isolate the portions P of the skeins S in the mating dye receiving recesses 40 and 41, 42 and 43, and 44 and 45, it being understood that the yieldability of the gaskets 46 and 47 will permit them to be compressed and intimately seal about the portions of the skeins which are located

therebetween and prevent escape of the dye solution from the dye recesses.

In order to provide means for gravitationally supplying and introducing the dye to the dye receiving recesses, a dye reservoir 55 is provided for each pair of mating recesses which is located above the recesses and each reservoir has leading downwardly therefrom a conduit pipe 56 controlled by a shut off valve 57. The conduit pipes 56 are respectively connected to and communicate with ports 58 leading to the corresponding recess in the lower dye block. Each recess of the upper dye block 31 is provided with a port 59 with which a conduit pipe 60 is connected and communicates. The pipes 60 are each provided with a T coupling 61, the vertical branch of which connects with a vertical pipe 62 having a cut off valve 63 from the top of which a combined transparent sight and vent tube 64 extends upwardly. The remaining horizontal branch of the T coupling 61 is connected with a nipple 65 having a check valve 66 which opens inwardly and closes outwardly. Each nipple is adapted to have attached thereto an air pressure hose, not shown.

The lower end of each reservoir 55 may be provided with a drain valve 67 and the conduit pipes 56 adjacent their connection with the lower valve block have interposed therein a T connection 68, the lower vertical branch of which connects with a drain pipe 69 having a cut off valve 70.

In operation, assuming that the skeins have been positioned and clamped between the dye blocks, as shown in Fig. 5, so that the portions P have been sealed off and isolated in the dye receiving compartments defined by the mating recesses, the valves 67 and 70 being closed, the operator opens the valves 63 and 57. The dye solutions in the reservoir which may be either of the same or different colors or shades, gravitationally run into the dye receiving compartments defined by the mating recesses, completely filling the same as they are vented by the air escaping through the ports 59, the pipes 60, T coupling 61, pipes 62, through the opened valves 63 and 45 the combined sight and vent tubes 64. When the dye shows in the sight tubes 64, the operator cuts off the valves 63 and 57 thereby sealing up the dye system completely. Air pressure may now be admitted through the nipples 65 and 50 check valve 66 to set up a pressure within the system so as to force and expedite the impregnation of the skein portions P with the dye. The drain valves 70 are then opened to permit the dye to be discharged from the system through the drain pipes 69 where the dye is caught into receptacles 71 placed thereunder to receive the same, the air pressure assisting in a rapid discharge and at the same time effecting a more rapid oxidation and setting of the dye in the impregnated skein portions P. The drain valves 70 are then cut off and the dye solutions in the receptacles 71 are poured back into the reservoirs 55 so that the operation may be repeated.

As illustrated, the lower dye block 30 is provided with guide rollers 75 around which the skeins are trained and the supports 11 and 12 at the front are provided with vertically adjustable brackets 76 which are normally drawn downwardly by contractile springs 77. A removable roller 78 is mounted for rotation in the brackets and is adapted to be turned by means of a crank 79. The skeins are trained around the roller 78 which is employed as a means for shift-

ing the skein to present other portions thereof for dyeing.

What is claimed is:

1. An apparatus for spot dyeing skeins of textile materials including a pair of separable dye blocks each having mating dye receiving recesses in the confronting faces thereof, yieldable gaskets on the confronting faces of the dye blocks framing the recesses, means for forceably compressing 5 the confronting gasketed faces into intimate sealing contact to close the open sides of the recesses to provide closed dye wells with the skeins located in place between and traversing the mating dye block recesses, valved means for 10 gravitationally filling the recesses with dye, valved means for venting the recesses, and valved means for draining the recesses.
2. An apparatus for spot dyeing skeins of textile materials including a pair of separable dye blocks each having mating dye receiving recesses in the confronting faces thereof, yieldable gaskets on the confronting faces of the dye blocks framing the recesses, means for forceably compressing 15 the confronting gasketed faces into intimate sealing contact to close the open sides of the recesses to provide closed dye wells with the skeins located in place between and traversing the mating dye block recesses, valved means for 20 gravitationally filling the recesses with dye, valved means for venting the recesses, and valved means for draining the recesses.
3. An apparatus for spot dyeing skeins of textile material including a base having spaced fixed 25 upright supports, a pair of superposed dye blocks each having mating dye receiving recesses in the confronting faces thereof, yieldable gaskets on said confronting dye block faces framing the 30 recesses, means mounting the lower dye block for horizontal swinging movement from an active position bridging the upright supports to an inactive position spaced from one of the supports to permit of the emplacement of the skeins 35 thereon in surrounding relation thereto, means carried by said upright supports for tensioning the skeins when in surrounding relation to the lower dye block, means mounting the upper dye block for vertical guided movement from a raised 40 position spaced above the lower dye block to a lowered position in engagement therewith, means for raising the upper dye block and for lowering the same to forceably compress the gasketed confronting faces thereof into intimate sealing contact to close the open sides of the recesses to provide closed dye wells with the skeins located in place between and traversing the mating dye block recesses, valved means for filling the recesses with dye, valved means for venting the recesses, and valved means for draining the recesses.

thereon in surrounding relation thereto, means mounting the upper dye block for vertical guided movement from a raised position spaced above the lower dye block to a lowered position in engagement therewith, means for raising the upper dye block and for lowering the same to forceably compress the gasketed confronting faces thereof into intimate sealing contact to close the open sides of the recesses to provide closed dye wells with the skeins located in place between and traversing the mating dye block recesses, valved means for filling the recesses with dye, valved means for venting the recesses, and valved means for draining the recesses.

4. An apparatus for spot dyeing skeins of textile material including a base having spaced fixed upright supports, a pair of superposed dye blocks each having mating dye receiving recesses in the confronting faces thereof, yieldable gaskets on said confronting dye block faces framing the recesses, means mounting the lower dye block for horizontal swinging movement from an active position bridging the upright supports to an inactive position spaced from one of the supports to permit of the emplacement of the skeins thereon in surrounding relation thereto, means carried by said upright supports for tensioning the skeins when in surrounding relation to the lower dye block, means mounting the upper dye block for vertical guided movement from a raised position spaced above the lower dye block to a lowered position in engagement therewith, means for raising the upper dye block and for lowering the same to forceably compress the gasketed confronting faces thereof into intimate sealing contact to close the open sides of the recesses to provide closed dye wells with the skeins located in place between and traversing the mating dye block recesses, valved means for filling the recesses with dye, valved means for venting the recesses, and valved means for draining the recesses.

ANGELO SORIANO.
